UNITED STATES PATENT OFFICE.

JULES ROUSSET, OF NOGENT-SUR-MARNE, FRANCE.

MANUFACTURE OF HOLLOW ARTIFICIAL TEXTILE ARTICLES.

1,427,330.

Specification of Letters Patent. Patented Aug. 29, 1922.

No Drawing.

Application filed May 8, 1922. Serial No. 559,491.

To all whom it may concern:

Be it known that I, JULES ROUSSET, a citizen of the Republic of France, residing at Nogent-sur-Marne, France, have invented 5 certain new and useful Improvements in the Manufacture of Hollow Artificial Textile Articles, of which the following is a specification.

Certain hollow artificial textiles are already known which are obtained by spinning an emulsion consisting of a spinnable liquid and of a neutral gas. Among the spinnable liquids which may be used are cellulosic solutions such as viscose, cupra-ammonium cellulose, and cellulose acetate, and other substances such as collodion, gelatin, etc.

In practice, however, the results obtained from the aforesaid process are incomplete.

The object of the present invention, therefore, is to provide an improved process for manufacturing hollow artificial textiles, which does not start, as has been the case heretofore, with an emulsion of a spinnable liquid and a neutral gas.

My improved process, which, as hereinabove described, is a division of the subject matter disclosed in my prior application, Serial Number 515,411, filed November 15, 1921, consists in incorporating with the spinning solution a substance designed to emit gaseous bubbles within the thread, after the latter has left the spinning head or draw-plate. This emission of gas may be induced either by chemical or by thermal action; and in the present case I have elected to claim specifically the use of such substances as are caused to emit the gas bubbles as a result of the chemical action taking place.

According to the first or preferred form of the process, I may incorporate a substance which will dissolve in the spinning solution, such, for instance, as a soluble alkaline carbonate; or I may incorporate a finely-divided or atomized insoluble carbonate. 45 Various other substances may be used which will give off, under chemical action, the gas bubbles required to form a hollow artificial textile; and it is to be understood, therefore, that the invention is not limited to the par-

ticular substances indicated above, which are merely mentioned by way of example. In any case, however, the substance utilized acts to produce in the thread issuing from the spinning apparatus, through a more or less hot coagulating acid bath, gas bubbles of various appearances according to operating conditions, the formation of the bubbles being due to the chemical reaction between the carbonate and the coagulating bath.

As an instance of production of gas bubbles by thermic action, there may be introduced into the solution to be spun a body or substance which will not give off vapors when cold, but will give off vapors when hot; for example, gasoline, carbon disulfide etc.

I claim as my invention:

1. In the manufacture of hollow, artificial textile articles, the steps of incorporating in a spinnable viscous solution a substance which will give off gas bubbles in the articles after the latter have left the spinning head; and then spinning the resultant solution to form the articles.

2. In the manufacture of hollow, artificial textile articles, the steps of incorporating in a spinnable viscous solution a substance which will react chemically with the coagulating bath to produce a series of gas bubbles in the articles after the latter have left the spinning head and have been passed through said bath; and then successively spinning the resultant solution to form the articles, and passing said articles through said bath.

3. In the manufacture of hollow, artificial textile articles, the steps of incorporating in a spinnable viscous solution a carbonate which will react chemically with the coagulating bath to produce a series of gas bubbles in the articles after the latter have left the spinning head and have been passed through said bath; and then successively spinning the resultant solution to form the articles, and passing said articles through said bath.

4. In the manufacture of hollow, artificial textile articles, the steps of incorporating in

a spinnable viscous solution an alkaline carbonate which will dissolve therein, and which will react chemically with the coagulating bath to produce a series of gas bubbles in
5 the articles after the latter have left the spinning head and have been passed through said bath; and then successively spinning

the resultant solution to form the articles, and passing said articles through said bath.

In testimony whereof I affix my signature. 10

JULES ROUSSET.

Witness:

GEORGE PASCAL CARRIÉRE.
